UNITED STATES PATENT OFFICE.

WALTER T. FERGUSON, OF ST. PAUL, VIRGINIA, ASSIGNOR OF ONE-HALF TO PELEG L. COLE, OF MAXWELL, VIRGINIA.

COIL ATTACHMENT.

Application filed October 27, 1924. Serial No. 746,224.

To all whom it may concern:

Be it known that I, WALTER T. FERGUSON, a citizen of the United States, residing at St. Paul, in the county of Wise and State 5 of Virginia, have invented a new and useful Coil Attachment, of which the following is a specification.

This invention relates to vibrator coil attachments and more particularly for coil 10 units used on Ford automobiles.

The object of the invention is to provide an inexpensive device for converting the coil unit such as is used on a Ford car into a threeway coil which can be used for many 15 purposes.

With the foregoing and other objects in view which will appear as the description proceeds, the invention resides in the combination and arrangement of parts and in 20 the details of construction hereinafter described and claimed, it being understood that changes in the precise embodiment of the invention herein disclosed may be made within the scope of what is claimed without 25 departing from the spirit of the invention.

In the accompanying drawings:—

Figure 1 represents a side elevation of a 30 Ford coil unit with this improved attachment shown applied;

Fig. 2 is a plan view thereof; and

Fig. 3 is a detail sectional view of a portion of the attachment and a side elevation of the adjacent portion of the unit.

In the embodiment illustrated a vibrator 35 coil unit 1 such as is usually employed on Ford cars is shown and which is equipped with the contact plates 2.

The device constituting this invention comprises a bracket 10 in the form of a 40 plate preferably constructed of such material as bakelite or other insulating material. This bracket has arms 11 extending laterally and turned downwardly at right angles located at one end thereof and provided with clamping screws 12 for securing 45 this portion of the bracket to the unit 1 and which holds the body of the plate spaced from the unit. The other end of said plate is bent downwardly at right 50 angles to the body portion thereof and is equipped with forwardly extending right angular arms 14 through which are inserted clamping screws 15 which are designed to secure this end of the bracket to the side 55 walls of the unit as is shown clearly in Figs.

1 and 2 and by means of which the bracket is held spaced from the unit.

Binding posts 16, 17 and 18 are carried respectively by the arm 13 of the bracket and by the body portion thereof near opposite ends of said body portion and are equipped with contact springs 19. Number 16 is the battery post, number 17 the plug or distribution post and number 18 the timer post. These posts are equipped with insulation blocks 20 arranged between the springs 19 and the bracket 10.

From the above description it will be obvious that this attachment may be quickly applied to a vibrator coil unit by simply 70 clamping it by means of the screws 12 and 15 to said unit and properly positioning the contact springs 19 relative to the contact plates and thereby convert the coil unit into a three way jump spark coil which may be 75 used not only for Ford car purposes but for many other purposes.

The device 10 is here described and shown as made of such material as bakelite which is an insulating material but obviously it 80 may be constructed of any other suitable material.

I claim:—

1. A device for converting a Ford coil unit into a three way coil comprising a 85 bracket having means for mounting on a coil unit in spaced relation thereto, binding posts carried by said bracket, contact springs carried by said posts and adapted to engage the contact plates of the coil unit. 90

2. The combination with a vibrator coil unit having contact plates; of a bracket having means for clamping it to said unit and holding it in spaced relation thereto, binding posts carried by said bracket and 95 equipped with contact springs for engaging the contact plates of the unit, and insulation arranged between the spring and the bracket.

3. An attachment of the class described 100 comprising a bracket substantially L-shaped in form the members of which are equipped with inwardly extending arms having clamping screws for detachably mounting the bracket on a coil unit, binding posts carried by the members of said bracket, contact springs carried by said posts and adapted to engage the contact plates of a coil unit, and means for insulating 105 the bracket from the springs. 110

4. A coil unit attachment of the class described comprising a substantially L-shaped bracket the members of which have inwardly extending arms at the side edges thereof equipped with clamping screws for securing the bracket to a unit, binding posts carried by the members of said bracket, contact springs carried by said posts and adapted to engage the contact plates of the unit,

and insulation blocks arranged between said 10 springs and bracket.

In testimony that I claim the foregoing as my own I have hereto affixed my signature in the presence of two witnesses.

WALTER T. FERGUSON.
